UNITED STATES PATENT OFFICE

FREDERICK R. ROBERTS, OF NEW YORK, N. Y.

HATBAND FASTENER

Application filed December 28, 1929. Serial No. 417,097.

The present invention relates to improvements in hat band fasteners, and has for an object to provide an improved device which may be applied to hat bands for holding the same in proper position on felt, straw or other types of hats, and which will maintain the band in proper position and at the same time will not be visible.

The invention also aims to provide a hat band fastener which may be secured to a hat band and furnished the hatter so that he can readily attach the bands to various types of hats and wherein the crowns of the hats are not perforated or otherwise disfigured by the use of the band, and wherein bands of various colors and ornamented in various ways may be quickly and easily applied to hats for use of college students and the like.

The invention further aims at the provision of a fastener which may be quickly and easily attached to the opposite ends of a hat band with one part of the fastener on the free end of the hat band to anchor it in place on the crown of the hat without perforating the crown, and the other part of the fastener may be secured in the bow of the band at the opposite end thereof and which is adapted to secure the bow to the free end portion of the band in overlapping relation therewith and to also engage the crown of the hat sufficiently to anchor the band thereon without perforating or mutilating the crown of the hat.

A still further object of the invention is to provide an improved fastener element having portions which lie in the outer fold of the bow on the band so as to hold the bow in spread flat position and to take up the strain imposed on the bow incident to securing the band to the hat so that the bow is maintained at all times in proper shape and the band is securely held in place.

With the foregoing and other objects in view, the invention will be more fully described hereinafter, and will be more particularly pointed out in the claims appended hereto.

In the drawings, wherein like symbols refer to like or corresponding parts throughout the several views.

Figure 1 is a perspective view of one type of hat having a hat band with the improved fastener applied thereto, and showing the initial step of applying the band to the hat.

Figure 2 is a similar view showing the band in applied position, the bow of the band being partly broken away to show the fastener element which is carried in the bow.

Figure 3 is a detail enlarged perspective view of the fastener element removed from the bow and showing the inner side of the fastener element with the inwardly struck and backwardly inclined prongs.

Figure 4 is an enlarged fragmentary horizontal view taken through one side of the crown of the hat with the band applied thereto and with the crown and part of the bow in section and showing the bow end of the band overlapping the free end of the band and anchored in the material of the side wall of the crown of the hat, and

Figure 5 is a detail perspective view of the anchoring portion of the fastener which is carried upon the free end of the band.

Referring to the drawings, 10 designates a hat band of ribbon or other suitable material or form and which may be made in different colors and may carry suitable ornamentations as desired. The hat band 10 is provided with one free end 11 and an outer end upon the outer side of which is formed or secured a bow 12. The free end 11 of the band is provided with an anchoring piece 13 which, as shown particularly in Figure 5, may be constructed of a length of wire which is bent substantially into an elongated loop of rectangular or other suitable form and which has a pin portion 14 emerging from the inner end of the loop intermediate the sides thereof and which extends lengthwise through the loop and across the closed end thereof and terminates in a slightly returned prong 15 at its outer end spaced outwardly from the loop 13. The pin portion 14 is adapted to be inserted through the free end 11 of the band near the extremity thereof and is adapted to lie against the inner side of the band with the loop 13 against the outer side thereof, the pin 14 being slightly bent outwardly at its free end and disposed with the prong 15 project-

ing outwardly from the outer side of the band. The band 10 is applied to the crown of the hat with the free end 11 overlapping the outer end of the band and the anchoring piece 13 being inserted through the free end 11 of the band near the extremity thereof and is adapted to lie against the inner side of the band with the loop 13 against the outer side thereof, the pin 14 being slightly bent outwardly at its free end and disposed with the prong 15 project-

ing inwardly for engagement in the side wall of the crown 16 of the hat body.

It will be noted from Figure 4 that the prong 15 is relatively small or short and is adapted to engage in the wall of the crown 16 to an extent sufficient only to anchor the free end 11 of the hat band. The hat band 10, in the usual manner, is adapted to be wound under tension about the crown 16 and with 5 the outer end of the band overlapping the anchored end 11 to the desired extent according to the size of the hat and with the lower edge of the band resting on the brim 17.

The main fastener element is carried in the 15 outer fold of the bow 12 and is thus located, as shown in Figures 1, 2 and 4, at the outer extremity of the band. This fastener element comprises a flat body portion of substantially V-shape having diverging arms 18, 20 the outer ends of which are preferably bent forwardly in an edgewise direction as at 19 and terminate in flat front edges adapted to engage in the crease of the fold of the bow 12 to hold it taut and extended, and to support 25 the bow against wrinkling or falling out of place.

If desired, this fastener element may be provided at its inner end and at its forward outer ends with openings 20 adapted to receive threads or the like therethrough for stitching or otherwise attaching the fastener element in the bow 12.

The outer plate portions 19 of the fastener are provided with inwardly struck prongs 30 21 which have relatively broad base portions at their forward ends where the prongs emerge from the plate portions 19, and the prongs taper to their rear free ends and are inclined inwardly and backwardly at a relatively slight angle so as to penetrate the inner end portion 11 of the band when the bow overlaps the same as shown in Figure 4, and to also bite or engage in the side wall of the crown 16 a distance sufficient only for anchoring the band in place. The band 10 when applied is adapted to be drawn or stretched into taut position and held in such position while the prongs 21 are engaged with the inner part 45 of the band so that when pressure is released 50 from the bow 12 the inherent resiliency of the band 10 is adapted to draw the bow 12 backwardly and engage and hold the prongs 21 through the inner part of the band and in anchoring engagement with the side wall 55 of the crown 16.

It is thus apparent that when the band is to be applied to the hat the prong 15 is engaged in the side wall of the crown 16, as shown in Figure 1, and the band 10 is drawn 60 taut and wrapped around the crown 16 until the bow 12 is brought into overlapping relation with the free end 11 of the band.

While maintaining the band under tension the bow 12 is pressed at its outer end inwardly toward the crown 16 so as to bring the free

ends of the prongs 21 against the outer side of the end 11 of the band. Pressure is now exerted on the outer end of the bow 12 to force the prongs 21 against the inner end of the band while at the same time the stretching of the band is relaxed sufficiently to permit the prongs to enter the inner portion of the band and bite into the wall of the crown 16.

It is apparent that the hat bands 10 may 70 be quickly applied by the retailers or purchasers to hats of felt, straw or the like and that the bands may be quickly interchanged or renewed and that the crown 16 of the hat is not perforated or mutilated in any way by the mounting of the hat band.

The prongs 21 are of relatively stiff material so that they are capable of withstanding the stretching pressure of the band 10 after the prongs have been inserted in the inner 85 portion of the band and inside of the hat. This inherent stiffness of the prongs 21 also holds the prongs in the desired angle to prevent the prongs from working entirely through the side wall of the crown 16.

Instead of using the form of Figure 5, pins for holding the plain end of the band to the hat, can be used. An ordinary common pin is used in case this little pin is lost.

The V shape metal fastener is designed in 90 this shape so as to hold the bow firm at the same time holding it apart. Also it does not show the attachment in any way when the band is on the hat whereas the old fashioned pins always did. It also can be pulled very 100 tight around a hat, the give of the band allowing for the snap back after the prongs are embodied in the felt of the hat. This also holds the band on very tight and it would be impossible to come off whereas the old fashioned pins would very often become loose and the band would fall off.

Another important feature is the fact that it cannot be distinguished from a sewed on band, it being impossible to tell which end is sewed and which end is pinned into the hat whereas the old fashioned type pin showed this distinctly. The prongs 21 can be given any suitable shape either more or less pointed than shown. The sewing holes 20 at the 115 apex, can be dispensed with, as the holes on the free ends 19 serve to hold the member quite sufficiently.

I desire it to be understood that the accompanying drawings show only one form of 120 which the invention is susceptible and I wish it to be understood that the right to make changes is reserved provided that such changes are within the scope of the following claims.

What is claimed is:—

1. As a new article of manufacture, a device for affixing hat bands, comprising a substantially V-shape frame of sheet metal adapted to be placed within the loop of the 130

bow of a hat band, said frame having flat plate portions on the outer ends of its diverging arms to engage in the crease of the bow and having pointed prongs integral with said 5 plate portions stamped inwardly therefrom and inclined backwardly, said prongs adapted to engage through the bow to hold the article therein and adapted to engage through the underlying end of the hat band when the 10 ends thereof are disposed in overlapping position upon a hat, said prongs being of a length adapted to project inwardly from the overlapping ends of the hat band and bite into the outer surface of the hat crown to anchor 15 the band thereon.

2. The combination with a suitable ribbon having a bow formation of a fastening device therefor comprising a substantially V-shape frame adapted to be placed within the loop 20 of the bow and having flat plate portions on the outer ends of the diverging arms for engaging the material of the bow at the fold and provided thereat with pointed prongs extending inwardly and rearwardly of the frame 25 for engagement through the bow and through the opposite end portion of the ribbon when the ribbon is overlapped about a hat or the like, said prongs being of sufficient length to extend inwardly beyond the overlapping 30 ends of the ribbon to bite into the outer surface of a hat crown to anchor the ribbon thereto.

3. A hat band fastener, comprising a V-shape flat frame having thread receiving per 35 forations at its inner pointed end and at its spaced outer ends for securing the flat frame in the bow of a hat band with the spaced ends in the outer crease of the bow to maintain the latter taut, said V-shaped frame having 40 a pair of prongs at its outer spaced ends with said prongs stamped inwardly from said ends and inclined rearwardly of the frame for engagement through the bow and adjacent portions of the hat band and adapted 45 to bite into the outer surface of the crown of the hat.

4. In combination with a hat band having a bow on one end thereof, a fastening member arranged within a loop of the bow sus 50 taining the walls thereof against collapse and having parts projecting from the plane of said member towards the inner end of the bow and protruding through one wall of said loop adapted to penetrate the other end of the 55 band and impale the wall of the hat crown to retain said band in its applied position.

5. In combination with a hat band having a bow on one end thereof, a multiple armed metallic fastening member enclosed within 60 a loop of the bow and permanently secured to one side thereof, each arm of said fastening member having a prong protruding through the side wall of said loop and adapted to penetrate the other end of the band adjacent 65 its opposite longitudinal edges and be im-

paled in the wall of the hat crown to retain said band in its applied position.

6. A hat band fastener comprising a multiple armed member adapted to be arranged within the bow loop of a hat band and having 70 means enabling said member to be permanently secured to one side of said loop, and the arms of said member being provided with attaching prongs adapted to impale the wall of a hat crown to retain the hat band in 75 its applied position.

7. A hat band fastener comprising a substantially rigid metallic member adapted for insertion in a bow loop of the hat band, said member having means enabling the same to be 80 permanently attached to one side of said loop and provided with spaced attaching prongs adapted to penetrate the hat band adjacent its upper and lower edges and be impaled in the wall of the hat crown to retain the hat 85 band in its applied position.

In testimony that I claim the foregoing as my invention, I have signed my name hereto.
